United States Patent

Des. 242,301
Patented Nov. 16, 1976

242,301

SUPPORT BASE FOR A BEVERAGE URN OR THE LIKE

Thomas E. Little, 2610 Nicholson St.,
Houston, Tex. 77008

Filed Apr. 14, 1975, Ser. No. 567,777

Term of patent 14 years

Int. Cl. D7—06

U.S. Cl. D7—130

FIG. 1 is a front view of a support base for a beverage urn or the like;

FIG. 2 is a top plan view;

FIG. 3 is a bottom view;

FIG. 4 is a side view; and

FIG. 5 is a back view.

I claim:

The ornamental design for a support base for a beverage urn or the like, substantially as shown.
